UNITED STATES PATENT OFFICE.

WILLIAM EDWIN RUSSELL, OF DANBURY, CONNECTICUT.

ELECTRIC TERMINAL CONTACT.

1,001,558.

Specification of Letters Patent. Patented Aug. 22, 1911.

Application filed January 31, 1911. Serial No. 605,796.

To all whom it may concern:

Be it known that I, WILLIAM EDWIN RUSSELL, a citizen of the United States, residing in the city of Danbury, county of Fairfield, 5 and State of Connecticut, have invented certain new and useful Improvements in Electric Terminal Contacts; and I do declare the following to be a full, clear, and exact description of the invention, such as 10 will enable others skilled in the art to which it appertains to make and use the same.

My invention relates to certain new and useful improvements in electric terminal contacts, and has for its object to secure the 15 electrical conductor to the contact post in such manner that not only is the conductor firmly anchored to the post, but the removable contact cap is invariably in firm electrical contact with both the conductor and the 20 post, and with these ends in view my invention consists in certain details of construction and combination of parts hereinafter fully described and then particularly pointed out in the claim which concludes this 25 description.

In the accompanying drawing Figure 1 is an elevation of the completed contact terminal—Fig. 2 an elevation with the contact cap removed—Fig. 3 a sectional elevation of the cap—Fig. 4 a sectional elevation of the post—Fig. 5 an elevation showing the wire inserted within the post preparatory to final connection therewith, and Fig. 6 a front view of the post with the electrical 30 conductor secured thereto.

Similar numerals of reference denote like parts in the several figures of the drawing.

1 is a post made of any suitable conducting material with a perforation 2 extending 40 therethrough from end to end. From the outer face of this post on opposite sides of the axial line of said perforation extend spaced contact fingers 3 whose outer surfaces are rounded and threaded as shown at 4, and at their bases these fingers are slightly recessed as shown at 5, for the purpose presently to be explained.

6 is the contact cap which is recessed in any suitable manner as shown at 7 and is 50 provided with a threaded portion 8 adapted to engage the threads 4 on the fingers 3 so that the cap may be firmly secured to the post 1. The lower wall of this recess 7 is chamfered as shown at 9, for the purpose presently to be explained.

10 is the electrical conductor of the usual insulated form and at Fig. 5 I have shown a portion of this conductor stripped of the insulation and inserted through the post 1 preparatory to being properly connected therewith, and this stripped portion is designated by the numeral 11.

After the parts have been assembled as shown at Fig. 5, the portion 11 is wound around one of the fingers 3 at its base within the recessed portion 5, this winding being effected by passing the portion 11 around the outside of the finger and thence within the space between the fingers, any surplus wire being then cut off, this winding being more particularly shown at Figs. 2 and 6. The cap 6 is then driven on these fingers, and the chamfered portion 9 will bind firmly against the bare wire 11 while the cap itself will seat firmly against the post, thus making a most excellent contact. By winding the wire in the manner aforesaid it is firmly anchored to the post and cannot be pulled therefrom, and the post with the conductor thus connected therewith may be 75 utilized in connection with any suitable contact cap so long as the latter is so constructed that it binds firmly against both the wire and post.

I have illustrated in the drawing a conventional form of contact cap but my invention is not limited to the employment of any special form of cap so long as it contacts firmly against the wire and post.

In the drawings I have shown the wire 11 wound around only one of the fingers, since this is sufficient for all practical purposes, but it of course will be understood that this wire may be wound around both of these fingers in any suitable and approved manner and I do not wish to be limited in this respect.

Having thus described my invention what I claim as new and desire to secure by Letters Patent is:—

The combination of the post having a perforation therethrough lengthwise thereof and provided with exteriorly threaded spaced fingers that extend from one end of the post parallel with said perforation and on opposite sides of the plane thereof, an insulated conductor wire passed through said perforation and having a stripped end which projects through said perforation between said fingers and then has a winding 105 110

contact with the lower portion of the latter, and a suitable contact cap provided with a recess chamfered near its outer end and having a threaded portion adapted to engage the threaded fingers whereby said cap may be driven firmly against said wire and post.

In testimony whereof I affix my signature in presence of two witnesses.

WILLIAM EDWIN RUSSELL.
